C. WACHTEL.

POCKET FLASH LIGHT.

APPLICATION FILED MAR. 4, 1916.

1,226,727.

Patented May 22, 1917.

UNITED STATES PATENT OFFICE.

CHARLES WACHTEL, OF JAMAICA, NEW YORK.

POCKET FLASH-LIGHT.

1,226,727.

Specification of Letters Patent. Patented May 22, 1917.

Application filed March 4, 1916. Serial No. 82,022.

To all whom it may concern:

Be it known that I, CHARLES WACHTEL, a citizen of the United States, and resident of Jamaica, county of Queens, city and State 5 of New York, have invented certain new and useful Improvements in Pocket Flash-Lights, of which the following is a specification.

One of the main objects of this invention 10 is to produce a pocket flashlight in which the battery will be contained in a case having a hinged cover, and to provide a device which will serve as a means for making and breaking the light circuit, and also as a 15 locking means to lock the hinged cover closed.

Another object of the invention is to provide a pocket flashlight with a casing having outwardly projecting flanges between 20 which the lamp bulb and the contact-making-and-breaking device are located, whereby the said flanges form guards or protecting means for said parts.

Another object of the invention is to 25 provide a flashlight in which the battery is contained within a case having a hinged cover, the lamp circuit-making-and-breaking device serving to lock the cover closed, means being provided whereby upon a 30 partial rotation of the contact-making-and-breaking device the cover may be released and the case opened for the removal of the battery, or for any other purpose.

There are other objects and advantages 35 of the invention, due to the details of construction, all of which will hereinafter appear.

In the drawings, Figure 1 is a perspective view of the device;

40 Fig. 2 a side elevation thereof, the cover being open;

Fig. 3 a transverse sectional view on the line III—III of Fig. 2, the cover being closed and locked;

45 Fig. 4 a vertical or longitudinal sectional view taken on the line IV—IV of Fig. 2;

Fig. 5 a front elevation, the operating button being removed and the shank holding said button being shown in sectional view;

50 Fig. 6 a top or plan view of the device; and

Fig. 7 a detail vertical sectional view on an enlarged scale, showing the lamp-circuit-making-and-breaking device.

55 Referring to the various parts by numerals, 1 designates the body of the case, said

body consisting of the frame 2 and the side portion 3 rigidly secured thereto. The side portion 3 extends beyond the frame 2 to form the protecting flanges 4 and 5. The 60 frame 2 is comprised of the front wall or part 6, the bottom wall 7 and the top wall 8, the top and bottom walls being integral with the front wall. One side of the case is hinged at 9 to form a cover 10, and said cover extends beyond the frame 2 to form the protecting flanges 11 and 12 which extend beyond the front wall and the top and bottom walls of said frame. The back of the casing is rounded as at 13, the hinge 9 being formed 65 down the middle of the said rounded portion. The top and bottom walls of the frame are rounded at their ends to fit the rounded portions of the side 3 and the cover portion 10. The hinge 9 joins the cover portion to 70 the rigid side portion.

Secured in the top wall of the frame, and extending into the case, is a lamp socket 14 adapted to contain a lamp bulb 15. Also secured to the top wall of the frame, adjacent the lamp socket, is an insulating plate 16. This plate extends into the case and is slotted at its inner end, as shown at 17. In this slot is secured a contact strip 18, by means of a terminal contact pin 19 which passes through the insulating plate and through the contact strip. The head of the contact pin is adjacent to the front wall of the case and is rounded to adapt it to be engaged by a contact point, as will be more fully hereinafter described. The battery 20 is provided with the usual upstanding contact point 21, which is adapted to fit in the slot of the insulating plate and to engage 90 the contact strip therein. The battery is 95 also provided with the spring contact point 22 which is adapted to engage the lamp terminal 23, as shown. By means of the arrangement of the contact points and strip described a considerable latitude of adjustment is provided, so that the battery connections may be brought into proper engagement with the terminals in the case, even though the batteries or battery terminals may vary slightly in length. This 100 avoids the necessity of springs for maintaining the battery contacts in engagement with the lamp terminals.

Slidably mounted on the inner side of the front wall of the case is a contact plate 24, 110 which is provided at its upper end with a contact point 25 which is adapted to engage

the terminal contact pin 19. The contact plate is held in position by means of a button 26 slidable on the outer side of the front wall of the case and rotatably connected to said contact plate by means of a stud 27, said stud being oblong in cross section. The slot 28 in the front wall of the casing, through which said stud extends, has two widths, the upper portion 29 being broader than the lower portion 30. The upper portion of the slot is broad enough to receive the stud when the button is turned to bring the longer diameter of the stud transversely of the slot. In this position of the stud the 10 sliding movement of the button is limited by the length of the broader portion of the slot. The narrower portion of the slot is only broad enough to receive the stud when the shorter diameter of the stud is transverse of said narrow portion of the slot. In 15 this position of the stud the sliding movement of the button is only limited by the entire length of the slot. It is, therefore, manifest that by properly arranging the 20 button the contact plate may be given a shorter or longer sliding movement. The contact button 26 is substantially oval or elliptical in shape and it is secured to the stud in such manner that the longer diameter of the stud will be transverse of the 25 button. By means of this arrangement the contact plate will have its limited movement when the longest diameter of the button is vertical, and said plate will have its longer 30 movement when the longest diameter of the button is transverse of the front wall of the case. The contact point and the terminal contact pin 19 are so arranged that they will be in engagement when the button is at 35 the lowermost point of its limited movement, so that when the button is arranged with its longer diameter vertical the lamp circuit will be completed when said button is forced downwardly to the limit of its movement, and said circuit will be broken when 40 the button is forced to the upper limit of its movement. The contact plate is slotted at its lower end, as at 31, to receive a guide pin 32 secured to the front wall of the casing. The contact plate springs inwardly 45 sufficiently to hold the button frictionally engaged with the front wall of the case, so that it will not be accidentally rotated.

On the edge of the contact plate, close to the edge of the front wall of the case, are formed two inwardly extending locking flanges 33, one near the top of the case and the other near the bottom thereof. On the cover portion 10 of the case are secured two locking lugs 34, said lugs being spaced from the cover part a slight distance in order to permit the locking flanges to engage said lugs and lie between them and the cover. The locking lugs and the locking 60 flanges are so arranged with respect to each

other that the flanges will be free of said lugs when the button has been moved downwardly to the limit of the narrow portion of the slot, but will be engaged to lock the cover in its closed position when the button is locked in the broader portion 29 of the slot, so that when the button is in position to act solely as a contact maker and breaker the cover will be locked in its closed position. When, however, the button is turned to permit the stud to pass down into the narrow portion of the slot, the locking flanges can be moved downwardly and freed from the locking lugs, thereby permitting the cover to be opened. From 70 the foregoing it is manifest that the 80 slideable button performs the double function of a contact maker and breaker and a lock-operating device. The contact performs the 85 double function of a contact device and lock.

What I claim is:

1. A flashlight comprising a casing composed of a body part, a cover hinged thereto, lamp terminals in the body part, a sliding contact plate, means exterior of the casing for moving the contact plate to make and break the lamp circuit, and means whereby the contact plate locks the cover in its closed position during the circuit 95 making and breaking operations and holds the cover closed while the lamp is lighted.

2. A flashlight comprising a casing formed with a body part and a cover hinged to said body part, lamp terminals in the body part, a slideable contact plate within the body part adapted to open and close the lamp circuit and formed with a cover-locking flange, a lug on the cover adapted to be engaged by said flange to lock the cover closed, an operating device for shifting the contact plate operable from the exterior of the casing and rotatably secured to said plate, and co-operating stops on said rotatable device and the casing adapted to limit the sliding movement of the contact plate when the operating device is reciprocated while in one rotatably adjusted position to open and close the lamp circuit without releasing the cover.

3. A flashlight comprising a casing formed of a body part and a cover hinged to the body part, lamp terminals in the body part, a shiftable contact plate within the body part, interlocking devices carried by the cover and contact plate, an operating device 120 for shifting the contact plate operable from the exterior of the casing and rotatably secured to said plate, and co-operating stops on said rotatable device and the casing adapted to limit the extent of movement of the contact plate when the operating device is actuated while in one rotatably adjusted position to open and close the lamp circuit without releasing the cover.

4. A flashlight comprising a casing formed 130

- of a body part and a cover part, lamp terminals in said casing, a contact plate formed with locking flanges, locking lugs formed on the cover and adapted to be engaged by the locking flanges on the contact plate, means adapted to move the contact plate to close the lamp circuit without releasing the cover and to impart a further movement thereto to unlock the cover, and a stop for limiting the movement of said means to circuit-closing position, said stop and contact-plate-moving means being relatively shiftable whereby said means may be operated to move the plate to unlocking position.
5. A flashlight comprising a casing formed with a body part and a cover, lamp terminals in said casing, a contact plate, a locking flange carried by said plate, a locking lug carried by the cover and adapted to be engaged by said locking flange, a rotatable button on the outer side of the casing and connected to the contact plate, means for limiting the movement of the contact plate when the button is in one position to complete the lamp circuit without releasing the cover, said contact plate being capable of a greater movement when the button is rotated to another position whereby the locking flange may be disconnected from the locking lugs to release the cover.
6. A flashlight comprising a casing formed with a body part and a cover, lamp terminals in said casing, a movable contact plate, and interlocking connections between the contact plate and the cover adapted to release the cover upon extended movement of said plate and normally holding the cover closed, said plate being shiftable to close the lamp circuit without releasing the cover.
7. A flashlight comprising a casing formed with a body part and a cover, lamp terminals therein, a contact plate, a slidable rotatable button on the outer side of the casing, a stud oblong in cross section connecting said button to the contact plate through a slot formed in the casing, said slot being of two widths whereby the button in one position will have a limited movement in the broader portion of the slot, and in another position may be moved the entire length of the slot, a locking device carried by the contact plate, and a corresponding locking device carried by the cover, said locking devices being disengaged through the longer movement of the contact plate.
8. A flashlight comprising a casing, a cover therefor, a lamp socket adapted to receive a lamp, an insulating plate secured to the casing adjacent the lamp socket and formed with a slot, a contact plate mounted in said slot, a terminal contact pin extending through said insulation and securing said plate in position, a slidable contact plate mounted in the casing, and means for moving said plate to engage the terminal contact pin.
9. A flashlight comprising a casing formed with a body part and a cover, a lamp socket in the top thereof adapted to receive a lamp bulb, a contact plate, a slidable button on the outer side of the casing and connected to said contact plate, and outwardly extending flanges around the edges of the casing on opposite sides of the lamp socket and of the slidable button.
10. A flashlight comprising a casing formed with a body part and a cover, lamp terminals in said casing, a movable contact plate, interlocking connections between the contact plate and the cover adapted to release the cover upon an extended movement of said plate and normally holding the cover closed, an adjustable operating device for moving the contact plate operable from the exterior of the casing, and means for limiting the extent of movement of said operating device when said device is actuated while in one adjusted position to open and close the lamp circuit without releasing the cover.

In testimony whereof I hereunto affix my signature.

CHARLES WACHTEL.
